SELF ADJUSTABLE TOWEL BAR BRACKET

Filed Oct. 21, 1930

UNITED STATES PATENT OFFICE

EDWIN REYNOLDS, OF VINELAND, NEW JERSEY

SELF ADJUSTABLE TOWEL BAR BRACKET

Application filed October 21, 1930. Serial No. 490,216.

The present invention has reference to improvements in supporting towel bar brackets and the like, and relates more particularly to a novel construction and arrangement of 5 the bracket and its towel bar holding supporting heads.

An object of my invention is the provision of a towel bar bracket with a plurality of towel bar holding heads and supporting 10 arms, one of said heads being non-adjustable with its supporting arms, and the other which is self adjustable with its supporting arms which would support substantially an indefinite number of various sizes of towel bars 15 of different diameters up to the full diameter of the non-adjustable stationary towel bar holding head, thereby making it unnecessary to have a separate size bracket head for each size of towel bars.

20 A further object of my invention is to provide a towel bar bracket with a non-adjustable bar holding head, and an adjustable bar size holding head which would keep the towel bar end knob spaced from the stationary non-adjustable towel bar holding 25 head and lie intervened between the towel bar end knob and the stationary non-adjustable bracket towel bar holding head and prevent any part of the towel bar knob from 30 entering the non-adjustable bar holding head regardless of the size of said knob.

A still further object of my invention is the provision of such a combination two headed towel bar holding bracket without 35 using any more material than is now used in the conventional type of bracket now in use, thereby providing a substantial, practical, simple and efficient combination towel bar bracket with two heads one of which is self adjustable and the other which is non-adjustable, which would be cheap to manufacture from a single piece of resilient sheet metal, thereby simplifying the construction and reducing the cost of production.

45 With these objects in view my invention consists in the construction, arrangement, and cooperation of the parts as will now be described in detail in connection with the accompanying drawings, in which:

50 Fig. 1 is a plan view of my new self ad-

justable towel bar bracket with non-adjustable and self adjustable towel bar size heads as it appears stamped out in the flat and before being bent and formed into shape.

Fig. 2 is a view of Fig. 1, in a more advanced stage of shaping.

Fig. 3 is a perspective view of my new self adjustable towel bar bracket as it appears finished and ready for use to mount to a support.

Fig. 4 is a top plan view of my new self adjustable towel bar bracket with a section of a towel bar within the towel bar holding heads and as it appears supported between the self adjustable towel bar size holding head showing the adjustable head frictionally engaged with the small size towel bar, and the bar suspended in space passing through the rigid non-adjustable towel bar holding head.

The invention is shown in the accompanying drawings, and what is now believed to be its preferred form in Fig. 1, is a single strip of resilient sheet metal 4, having at 5, 5, apertures for screws or nails near each of its ends, spaced on the said strip of sheet metal 4, and preferably at its transverse center at 6, the said strip of metal 4, has a predetermined size slot 7, formed therein extending equidistant from its mid center 6, and towards its apertured ends 5, 5, and transversal to its longitudinal center of the said strip 4, of Fig. 1, the said strip 4, is then slotted at its longitudinal center at 8, 8, in opposite directions from the said predetermined slot 7, and equidistant therefrom forming a continuous T shaped slot, and the said T shaped slot dividing off and spacing from the body section 10, of the metal strip 4, two elongated rectangular body members 9, 9, each having a free end 11, 11, disposed towards each other and spaced from each other by the T shaped slots 7, and 8, 8, and the said members 9, 9, being integral at their opposite ends with the body 4, at 12, 12, of Fig. 1, the said strip of metal 4, is then folded and bent upon itself at its mid transverse center to form a towel bar supporting bracket with two towel bar holding heads 13, and 14, of Fig. 3, one of said heads 13,

being an integral annular circular like head with rigid parallel arms at right angles to itself 15, 15, which are integral with the relative wider fastening plate supporting arms 17, 17, and the head 13 being a one piece and of a larger diameter than the second adjustable head 14, as shown in Fig. 3, the adjustable towel bar holding head 14, is of a smaller diameter than the nonadjustable head 13, when formed at the time of manufacture, the rectangular body members 9, 9, of Fig. 1, are formed into a circular head 14, with parallel arms at right angles to the head 13, and the adjustable head would be transversely divided at its front mid center at 20, as shown in Fig. 3, the adjustable towel bar holding head 14, would be integral with its supporting arms 16, 16, and the said arms 16, 16, would be integral with the relative wider fastening plate arms 17, 17, and each pair of arms 15, 15, and 16, 16, are exactly alike in extent and direction and parallel with each other, and one of said pair of supporting arms 15, 15, would be rigid with the fastening plate arms 17, 17, and the other pair of arms 16, 16, would be resilient and movable, adjustable with its bar holding head 14, as shown in Fig. 2, and 3, it will be apparent that when the blank 4 of Fig. 1, is cut and formed as shown and bent and formed into shape into a supporting towel bar bracket with towel bar holding heads as shown in Fig. 2, and Fig. 3, the bracket would have its towel bar holding head and its supporting arms divided longitudinally at its center at 19, Fig. 2, by means of the slots 8, 8, of Fig. 1, and a double annular two headed towel bar holding bracket would be provided each having a pair of supporting arms 15, 15, 16, 16, and the said heads and arms would be spaced apart laterally, horizontally by the slots 8, 8, side by side as shown in Fig. 2, at 13, 14, separate from each other and adapted to act independent of each other, and it will be further apparent that when the adjustable towel bar holding head 14, is divided at its transverse center at 20, Fig. 3, the said head 14, would have a divided head with upper and lower sections 21, 21, integral with their supporting arms 16, 16, as shown in Figs. 2 and 3, it will now be apparent that a towel bar bracket has been provided with two annular towel bar heads 13, and 14, one of which is stationary and one piece 13 rigid with its supporting arms 15, 15, and the other head 14, adjustable for frictionally engaging and holding towel bars of various diameters to the full capacity of the stationary bar holding head 13, of Figs 2 and 3. It will now be apparent that when a towel bar 22, of Fig. 4, is inserted between the supporting arms 17, 17, and brought forward within the towel bar holding heads 13, 14, of the bracket as shown in Fig. 4, the said adjustable, movable upper

and lower half 21, 21, of the towel bar holding head 14, would be forced apart at their transverse divided center 20, of Fig. 3, and by means of the resiliency of the adjustable head 14, supporting arms 16, 16, there would be resisting force exerted by the said arms to the upper and lower half 21, 21, of the adjustable head 14, of Fig. 3, causing the adjustable head 14, to frictionally, and substantially engage the said towel bar 22, and to hold the said bar 22, suspended in space within the rigid stationary towel bar holding head 13 as shown in Fig. 4, and it will be clear that the said adjustable head 14, will hold any size towel bar up to the full diameter of the said stationary towel bar holding head 13 of Figs. 3 and 4. It will be further apparent that when the towel bar brackets are mounted to a support by means of its fastening plates 18, 18, with screws Fig. 3, with the adjustable bar holding head 14, positioned next to the towel bar knob 23 of Fig. 4, the said adjustable head 14, would lie intervened between the towel bar knob 23 of the towel bar 22, and the stationary towel bar holding head 13, of larger diameter, and keep the said towel bar knob 23, spaced from the head 13, and prevent a towel bar knob of small diameter from making contact or entering the said stationary towel bar holding head 13, when mounted therein, as shown in Fig. 4, it will be clear that when the brackets are so manufactured they would be reversible and could be used for a right side or left side towel bar bracket and keep the towel bar knob spaced from the stationary towel bar head 13 and from entering the same.

It will now be apparent that a substantial, practical, simple and efficient adjustable towel bar bracket with non-adjustable and self adjustable towel bar size holding heads have been provided and formed from a single piece of resilient sheet metal, which will be cheap to manufacture.

Although I have shown by way of example in Figs. 1, 2, 3, 4, the preferred form of my invention, I want it particularly understood that I do not limit myself to this exact shape bracket, but reserve unto myself the right to vary the shape within certain limits of what is disclosed and what is claimed without departing from the spirit of my invention.

What I claim is:—

1. In a sheet metal towel bar bracket consisting of a sheet metal blank strip of resilient sheet metal having cut out at its transverse mid center a predetermined size slot extending equidistant from its mid center in opposite directions and transversal to its longitudinal center of the said metal strip body, and the said blank body having formed, cut at its longitudinal center extending longitudinal slots in opposite directions equidis-

tant from the said predetermined transverse slot, and the said longitudinal slots each extending into the transverse slot, forming a continuous extended T shaped slot in the said metal blank body, and the said blank body having spaced apart by the said slots from its body section two elongated rectangular body members with free ends disposed towards each other and integral with the blank body at their opposite ends said metal blank being folded upon itself at its transverse center to form a towel bar bracket having a connected rigid one piece towel bar holding head, and an adjustable towel bar holding head transversely divided at its front mid center said heads being laterally, horizontally spaced from each other by a longitudinal slot and side by side said heads each having a pair of supporting arms integral with a relative wider fastening plate arm with apertured fastening plates at angles to the said wider arms as described.

2. In a towel bar bracket a resilient sheet metal blank being cut and formed as described, said sheet metal blank being folded upon itself at its transverse center to form a towel bar bracket with two towel bar holding heads, one of said heads being rigid and a connecting one piece with its supporting arms and non-adjustable and the second head being of a lesser diameter than the rigid head and being adjustable when formed and having separate supporting arms spaced from the first towel bar holding head and parallel thereof and the said supporting pairs of arms of each towel bar holding head being integral with the relative wider fastening plate arms and the relative wider fastening plate arms being bent at right angles to themselves in opposite directions to form fastening plates and the said plates having apertures for screws.

3. In a supporting towel bar bracket formed from a single piece of resilient sheet metal having two towel bar holding heads laterally spaced from each other, one of said heads being a connected one piece with its supporting arms, and the second head being of a less diameter than the first head and being transversely divided and having resilient parallel arms at right angles to the said head and the said second head being adjustable for various sizes of towel bars.

4. In a sheet metal towel bar bracket having two towel bar holding heads, spaced horizontally apart by longitudinal slots and side by side, each head having a separate pair of parallel arms for supporting same, said pairs of arms being spaced apart and side by side, and each pair of arms being integral with a relative pair of wider fastening plate arms, and the said fastening plate arms having apertured supporting plates for mounting same.

5. In a sheet metal towel bar bracket formed from a single piece of resilient sheet metal having two towel bar supporting annular heads, spaced laterally apart from each other for supporting a towel bar therein. 79

6. In a sheet metal supporting towel bar bracket having two annular towel bar holding heads spaced horizontally apart by a slot, one of said annular heads being rigid connecting one piece head with its supporting arms and of a larger diameter than the second head, and the second head being divided at its front transverse center and having a movable, adjustable upper and lower half head, and the said second head having resilient parallel supporting arms integral with a relative wider pair of fastening plate arms, and the said fastening plate arms having apertured fastening plates to mount same. 75

7. In a sheet metal towel bar bracket consisting of a sheet metal blank folded upon itself to form a towel bar bracket with two annular towel bar holding heads spaced apart by a longitudinal slot, said heads having parallel supporting arms side by side. 80

8. In a sheet metal towel bar bracket having two towel bar annular holding heads formed from a single piece of resilient sheet metal having fastening plates, each fastening plate having a relative extending wide arm, and each of said arms having a pair of extending arms of lesser width connected thereto, and each pair of arms of lesser width being spaced apart laterally, horizontally by a longitudinal slot and parallel with each other and side by side, one of said lesser width pair of arms having connected thereto a one piece annular towel bar holding head formed thereon of a large diameter and rigid with the said supporting pair of arms, and the second pair of arms having a towel bar holding head of lesser diameter than the stationary rigid head formed thereon and being divided at its transverse mid center and adapted to be adjustable and to frictionally engage and hold towel bars of various diameters when inserted within same, each pair of arms with their supporting towel bar holding heads being complete within itself. 103

9. In a sheet metal towel bar bracket formed from a single piece of resilient sheet metal cut as described, having two towel bar holding heads, one of said heads being of a larger diameter than the other and each towel bar holding head having a separate pair of supporting arms spaced laterally apart by a slot, and each pair of arms being spaced one above the other, and the said pairs, of arms each being integral with a relative wider fastening plate arm. 115

10. In a sheet metal towel bar bracket having two annular towel bar holding heads, one of said heads being an integral one piece with its supporting arms and of a larger diameter than the second adjustable bar hold. 125

ing head, said heads being spaced apart by a slot, and the second head adapted to frictionally engage a towel bar therein and to horizontally hold and suspend the said towel bar in space within the larger rigid towel bar holding head as described.

11. In a sheet metal towel bar bracket having a rigid annular one piece towel bar holding head, a second annular towel bar holding head of a lesser diameter than the rigid head spaced horizontally, laterally from the rigid one piece annular head by a longitudinal slot, and the second head being divided at its transverse center, each head having a pair of parallel supporting arms exactly alike in extent and direction and each pair of arms being integral with a relative wider fastening plate arm, and the said divided head having its supporting pair of arms resilient and adapted to exert force to the adjustable bar holding head and upon a towel bar when inserted within the said adjustable towel bar holding head, and the said towel bar holding heads and their supporting arms being adapted to act independently of each other.

12. In a sheet metal towel bar bracket having two towel bar supporting heads, one of said heads being an integral one piece with its supporting arms, and the second head being of a lesser diameter and divided at its transverse center, having upper and lower movable sections and the said sections having resilient arms and the said divided head and its supporting arms being spaced horizontally from each other by an extended longitudinal slot.

13. In a sheet metal towel bar bracket consisting of a strip of resilient sheet metal, bent upon itself intermediate its ends to form a towel bar bracket with two annular towel bar holding heads spaced apart by an intervening longitudinal slot, said heads having a plurality of arms integral thereof, and the said arms being integral with a relatively wider pair of supporting arms each having a fastening plate with apertures for screws to mount same.

EDWIN REYNOLDS.
